UNITED STATES PATENT OFFICE

146,567

DESIGN FOR A LEATHER JACKET

Jack Greenberg and Benjamin Fortgang,
New York, N. Y.

Application October 19, 1946, Serial No. 134,093

Term of patent 14 years

(Cl. D3—4)

To all whom it may concern:

Be it known that we, Benjamin Fortgang and Jack Greenberg, both citizens of the United States of America, residing at New York city, county of New York, and State of New York, have invented a new, original, and ornamental Design for a Leather Jacket, of which the following is a specification, reference being had to the accompanying drawing, forming part thereof, wherein,

We claim:

The ornamental design for a leather jacket, substantially as shown.

BENJAMIN FORTGANG.
JACK GREENBERG.
